UNITED STATES PATENT OFFICE.

SAMUEL OLSON, OF CHICAGO, ILLINOIS.

TRAY-ELEVATOR.

1,351,215.

Specification of Letters Patent. Patented Aug. 31, 1920.

Application filed January 5, 1914. Serial No. 810,357.

To all whom it may concern:

Be it known that I, SAMUEL OLSON, a citizen of the United States, residing at Chicago, in the county of Cook and State of Illinois, have invented certain new and useful Improvements in Tray-Elevators, of which the following is a specification, reference being had to the accompanying drawings, forming a part thereof.

10 This invention relates to certain features of a package conveyer of the type commonly known as a tray elevator, having to do particularly with improved means for discharging loads therefrom. It comprises the features and combinations of elements described herein and shown in the drawings as indicated by the claims.

In the drawings:—

Figure 1 is a sectional elevation of an elevator and certain appurtenances thereto embodying this invention.

Fig. 2 is a plan section taken as indicated at line 2—2 on Fig. 1.

The conveyer illustrated in the drawings 25 consists essentially of one or more endless chains, A, mounted for travel over head wheels indicated at B, and foot wheels not shown, together with trays, C, carried by the chains and guided as hereinafter described. As illustrated in the drawings, this conveyer is designed primarily for use as an elevator, its trays being symmetrically designed so as to be available for carrying loads upward along one ply of the chain, 30 A, and adapted for transferring other loads downward along the other ply of the chain, notwithstanding the fact that such trays are inverted in passing around the head wheels at B. With this object in view each tray is 35 designed to extend to one side of its pivotal point of engagement with the chain at C¹, but is provided with arms, C² and C³, which extend to the other side of such point of engagement and are fitted with guide rollers, C²⁰ and C³⁰, respectively, for which guide channels are formed by oppositely facing angle rails, D^x and D^y, fixedly positioned with respect to the path of travel of the chain, A. As indicated in the drawings, the 40 arms, C² and C³, diverge simultaneously from the medial plane of the tray, C, and are exactly similar in formation, thus adapting the tray to support a load with equal efficiency upon the other face and at either 45 ply of the traveling belt, A. For automatically discharging the contents of a tray as

the latter passes the particular floor, E, at which the load is to be delivered the guide rail, D^x, is formed with an outwardly deflected portion, D^z, so that in following this 60 portion of the track the tray will assume a tilted position, as indicated in dotted lines in Fig. 1, and will gravitationally discharge the load. This deflected portion, D^z, of the rail, D^x, is preferably a permanent and fixed 65 feature, but may be thrown out of service by the insertion of a bridge piece, D, which is hinged to the fixed rail, D^z, so as to be laterally movable into and out of bridging position, as more clearly indicated in Fig. 2. 70 From this view it will be understood that similar guide devices are provided at each side of the path of travel of the trays and that the two hinged bridge sections, D, D, are connected together for simultaneous 75 movement by a link, F, extending transversely of the conveyer between the two plies of the chain and pivotally connected with bell cranks, F¹, which in turn are linked, respectively, to the operating arms, D¹, of the 80 bridge members, D. One of the bell cranks, F¹, is provided with an operating lever, G, working over a notched segment, G¹; with the lever in the position shown it will be seen that the bridge members, D, positioned 85 as indicated in full lines in Fig. 2, render the guide channel perfectly straight so as to avoid tilting the trays, C, as they pass but that when the lever is moved to the segment notch, G², the bridge members will assume 90 the positions indicated in dotted lines, swinging clear of the path of the guide rollers and permitting them to follow the deflected track, D^z. This feature is illustrated on the up-going side of the elevator 95 but is obviously applicable to the descending side as well.

It should be noted that the deflected rail, D^z, being bent outwardly in the direction in which the load is to be discharged from the 100 trays, C, causes the tray to move bodily in that direction a short distance as it is tilted, thus tending to give its load an impulse which will assist the tray.

It will be seen from the plan view that 105 the trays are preferably composed of a series of arms or fingers, C^x, transversely spaced apart, and for removing loads from the trays in their downward travel there may be provided at each floor, H, an inclined runway, J, of bars, J^x, positioned to intermember 110 with the arms, C^x, of the conveyer trays.

This run-way is pivotally mounted in an opening, K^1 , in the vertical wall, K , which incloses the elevator, and when not in use may be rotated through the arc indicated in 5 dotted lines at L , so as to serve as a guard grating for the opening, K^1 .

I claim:—

1. In combination with a continuous belt, a tray pivoted thereto upon a horizontal axis, 10 said tray being adapted to extend horizontally and having both its faces arranged to support a load, two guide rollers associated with the tray and mounted at equal distances above and below the pivotal axis respectively and at a substantial distance from the axis in the direction opposite to that in which the tray extends, together with means for mounting and driving the belt, and a guide channel positioned back of the plane 15 of the belt to receive the reaction of the said rollers upon its opposite walls respectively.
2. In combination with a continuous belt, a tray pivoted thereto upon a horizontal axis, 20 said tray being adapted to extend horizontally and having both its faces arranged to support a load, two guide rollers associated with the tray and mounted at equal distances above and below the pivotal axis respectively and entirely beyond the plane of the belt in 25 the direction opposite to that in which the

tray extends, together with means for mounting and driving the belt, and a guide channel positioned back of the plane of the belt to receive the reaction of the said rollers upon its opposite walls respectively. 35

3. In a conveyer comprising a belt mounted for vertical travel, a tray pivotally engaged therewith and extending to one side of the axis of engagement, upper and lower guide rollers rigidly associated with said tray, and a guide channel positioned to receive the reactions of said rollers upon its opposite walls respectively, said lower roller being positioned to engage such guide below the plane of the tray, and the vertically extending part of the wall of the guide channel which supports the upper roller having a portion which is deflected away from the opposite wall for tilting the tray in its travel thereover whereby said tilting of the tray is 40 accompanied by a slight bodily movement thereof about the lower roller in a direction 45 for discharge of the load. 50

In testimony whereof I have hereunto set my hand at Chicago, Illinois, this 31st day of December, 1913.

SAMUEL OLSON.
